UNITED STATES PATENT OFFICE.

ROBERT NEWALL, OF TORONTO, CANADA.

STALL-BOTTOM.

No. 801,900.

Specification of Letters Patent.

Patented Oct. 17, 1905.

Application filed January 17, 1905. Serial No. 241,510.

To all whom it may concern:

Be it known that I, ROBERT NEWALL, manufacturer, a subject of the King of Great Britain, residing in the city of Toronto, in the county 5 of York, in the Province of Ontario, Canada, have invented certain new and useful Improvements in Stall-Bottoms, of which the following is a specification.

My invention relates to improvements in stall-bottoms; and the objects of my invention are, first, to provide an absolutely sanitary stall-bottom; secondly, to enable the horse to stand in water in order that his hoofs may be softened; thirdly, to provide a stall-bottom 15 so that in case the drains connected therewith should be choked it will be an easy matter to flush same out; and it consists, essentially, of a basin divided into two compartments, one compartment being larger than the other, 20 and a plurality of bars or cross-pieces removably supported within said larger compartment and drain connections for said basin, as hereinafter more particularly explained.

Figure 1 is a general perspective view of 25 my preferred form of stall-bottom. Fig. 2 is a vertical cross-section on the line $a'b$, Fig. 1, looking in the direction indicated by arrow. Fig. 3 is a longitudinal vertical section through my stall-bottom. Fig. 4 is a perspective view of part of the outer portion of 30 the stall-bottom, showing same constructed with plates to prevent the droppings from passing into the basin; and Fig. 5 is an enlarged perspective view of two of the bars or cross-pieces provided with a plate.

In the drawings like characters of reference indicate corresponding parts in each figure.

A represents the vertical sides of the stall, 40 and B the usual sides of the stall-bottom, which preferably slope inward. The stall-bottom is, of course, preferably made of concrete or similar material, and in same I construct a basin C, in which I preferably place a correspondingly-shaped metal basin D. Suitably supported within the basin D are a series of bars or cross-pieces E, the top portions of 45 which are flush with the top edge of said basin. As shown, these bars or cross-pieces are not fitted one against the other, and at their ends they rest upon shoulders a and a' , constructed in the basin D, or may be supported in any other suitable manner. In order to give the 50 said bars or cross-pieces support midway their length, I secure in the basin D support-

ing means separate from said bars or cross-pieces. My preferred means for supporting said bars or cross-pieces consists of a plurality of pins F, which fit into holes G, made in the under side of the bars or cross-pieces E. 60

As shown, the basin D gradually gets deeper from its inner end H toward its outer end I. It will also be noticed that the bottom sides f of the basin D slope inward toward its middle, thus making the bottom for the said 65 basin trough-shaped, so as to facilitate drainage. By means of any suitable drain connection J connected thereto the material is carried away from the basin D. In order to enable the horse's front feet to be placed in 70 water without disturbing the bars or cross-pieces E, I secure to or form part of said basin a partition L, which divides the basin D into two compartments K and K'. Flush with the top of the bars or cross-pieces E is 75 a covering M, which rests upon the top of the partition L and against the inner ends of the cross-pieces E and upon the shoulder a' , formed in the inner end H of the basin D. By removing the cover M and filling the compartment K with water the horse's front feet are placed therein for the purpose before described. By means of the passage-way or 80 opening N in the partition L the compartment K drains into the compartment K'. In order 85 to retain water in the compartment K, the passage-way or opening N is plugged up by any suitable means. When through using the compartment K, the plug is removed from the opening N and the cover M replaced. 90

When it is desired to place the horse's back feet in water, the bars or cross-pieces E are removed and the drain connection J plugged up, so as to prevent the water from running away. 95

To prevent as far as possible the droppings from passing into the basin D, I secure at the outer ends of the bars or cross-pieces E a series of plates O. These plates are provided with horizontal flanges o' and o'' , which are countersunk in the upper surfaces of the bars or cross-pieces E, and their inner edges are constructed at a downwardly-inclined angle, so as to provide a trough o^3 for the purpose of drainage. As will be seen from Figs. 4 100 and 5, these plates O are secured by the screws o^4 or in any other suitable manner. Any one bar or cross-piece may be removed without necessitating the removal of the others. 105

As will be seen from Figs. 2 and 3, the bars 110

or cross-pieces E do not rest upon the bottom of the basin.

Although I preferably use a metal basin or lining within the basin C, I do not confine myself to using same, and for the purposes of the claims the mere expression "basin" must be read as meaning the concrete basin C. Although shown in the drawings that the compartments K and K' are formed in the integral basin D, it must be clearly understood that I do not confine myself to this construction. I may dispense altogether with the metal basin D and merely use the basin C and divide same into two compartments by means 15 of a suitable partition.

It will of course be understood that the drain connection J may be constructed so as to form the well-known trap. As there will be more or less water in the basin D, it will 20 be understood that no odor can get up through the drain-pipes into the stable. Each stall-bottom is a separate unit.

I do not confine myself to the construction herein shown and described, as same can be 25 altered in various ways without departing from the spirit of my invention.

What I claim as my invention is—

1. A stall-bottom comprising a basin; a partition therein dividing said basin into two 30 compartments one compartment being larger than the other; a plurality of bars or cross-pieces removably supported within said larger compartment, and drain connections therefor.

2. A stall-bottom comprising a basin constructed with a trough-shaped bottom that 35 throws the drainage toward its middle and being further constructed so as to get deeper from its inner end to its outer end; a partition therein dividing said basin into two compartments one compartment being larger than the other; a plurality of bars or cross-pieces removably supported within said larger compartment, and drain connections therefor.

3. A stall-bottom comprising a metal basin; 45 a partition therein dividing said basin into two compartments one compartment being larger than the other; a plurality of bars or cross-pieces removably supported within said larger compartment, and drain connections therefor.

50 4. A stall-bottom comprising a metal basin constructed with a trough-shaped bottom that throws the drainage toward its middle and being further constructed so as to get deeper from its inner end to its outer end; a partition therein dividing said basin into two compartments one compartment being larger than the other; a plurality of bars or cross-pieces removably supported within said larger compartment, and drain connections therefor.

55 5. A stall-bottom comprising a basin; a partition therein dividing said basin into two compartments one compartment being larger than the other; a covering for said smaller compartment; a plurality of bars or cross-pieces removably supported within said larger com-

partment, the said smaller compartment draining through said larger compartment, and drain connections therefor.

6. A stall-bottom comprising a basin; a partition therein dividing said basin into two compartments one compartment being larger than the other; a covering for said smaller compartment; a plurality of bars or cross-pieces removably supported within said larger compartment, the said smaller compartment draining 70 through said larger compartment; drain connections therefor, and means in said basin for giving said cross-bars intermediate support.

7. A stall-bottom comprising a basin; a partition therein dividing said basin into two compartments one compartment being larger than the other; a covering for said smaller compartment; a plurality of bars or cross-pieces spaced apart and removably supported within 75 said larger compartment, the said smaller compartment draining through said larger compartment; drain connections for said basin; means in said basin for giving said cross-bars intermediate support, and a plurality of plates 80 secured to said cross-pieces near their outer ends so as to bridge the openings between said bars for any suitable distance.

8. A stall-bottom comprising a metal basin; a plurality of bars or cross-pieces removably 85 supported within same, and a plurality of vertical pins secured to or forming part of said metal basin and resting in holes in said bars or cross-pieces so as to give them intermediate support.

9. A stall-bottom comprising a metal basin provided with a trough-shaped bottom so as to throw drainage toward its middle and being further constructed so as to get deeper from its inner toward its outer end; drain connections for said basin; a partition secured to or forming part of said basin near its inner end thus dividing same into a large and a smaller compartment; a plurality of bars or cross-pieces removably supported within said 105 larger compartment, and a removable covering for said smaller compartment, the drainage from said smaller compartment draining through said partition.

10. A stall-bottom comprising a basin; a 110 plurality of bars or cross-pieces spaced apart and removably supported within same, and a plurality of plates secured to said cross-pieces or bars near their outer ends so as to bridge the openings between said bars for any suitable distance.

11. A stall-bottom comprising a metal basin; a plurality of bars or cross-pieces spaced apart and removably supported within same, and a plurality of plates secured to said cross-pieces 115 or bars near their outer ends so as to bridge the openings between said bars for any suitable distance.

12. A stall-bottom comprising a metal basin; a plurality of bars or cross-pieces spaced apart 120

and removably supported within same, and a plurality of plates secured to said cross-pieces or bars near their outer ends so as to bridge the openings between said bars for any suitable distance, the said plates being provided with drainage-troughs extending down into the space between said bars.

13. A stall-bottom comprising a metal basin; drain connections for said basin; a partition secured to or forming part of said basin near its inner end thus dividing same into two compartments one being larger than the other; a plurality of bars or cross-pieces supported in said larger compartment, and a removable covering for said smaller compartment, the water from said smaller compartment draining through said partition.

14. In a stall-bottom the combination with two bars or cross-pieces spaced apart, of a

plate provided with a drainage-trough extending down into the space between said bars and two horizontal flanges resting upon said bars, the said plate being secured by means of one of its flanges to the bar said flange rests upon.

15. A stall-bottom comprising a basin; a partition, secured to or forming part thereof, dividing said basin into a large and smaller compartment, the smaller compartment designed to drain through said partition into said larger compartment, and drain connections for said basin.

In testimony whereof I have signed my name to this specification in the presence of two subscribing witnesses.

ROBERT NEWALL.
